US00D961501S

(12) **United States Design Patent** (10) Patent No.: **US D961,501 S**
(45) Date of Patent: **** Aug. 23, 2022**

(54) **BATTERY PACK FOR A CAMERA**

(71) Applicant: **NIKON CORPORATION**, Tokyo (JP)

(72) Inventors: **Yoshihisa Saito**, Tokyo (JP); **Shiki Inoue**, Tokyo (JP); **Atsushi Hamazaki**, Tokyo (JP)

(73) Assignee: **NIKON CORPORATION**, Tokyo (JP)

(**) Term: **15 Years**

(21) Appl. No.: **35/511,674**

(22) Filed: **Mar. 15, 2021**

(80) **Hague Agreement Data**

Int. Filing Date: **Mar. 15, 2021**

Int. Reg. No.: **DM/213457**

Int. Reg. Date: **Mar. 15, 2021**

Int. Reg. Pub. Date: **Apr. 9, 2021**

(30) **Foreign Application Priority Data**

Sep. 30, 2020 (JP) ..... 2020-020885 D

(51) **LOC (13) Cl.** **13-02**

(52) **U.S. Cl.**

USPC **D13/103**

(58) **Field of Classification Search**

USPC D13/103; D16/237, 242
CPC .. H01M 10/425; H01M 50/247; G03B 17/56;
G03B 17/02

(57) **CLAIM**

The ornamental design for a battery pack for a camera, as shown and described.

DESCRIPTION

1. Battery pack for a camera

1.1 : Front perspective view

1.2 : Back perspective view

1.3 : Front

1.4 : Back

1.5 : Top

1.6 : Bottom

1.7 : Right

1.8 : Left

The broken lines in the figures form no part of the claimed design.

1 Claim, 8 Drawing Sheets
